UNITED STATES PATENT OFFICE.

RUDOLF GOMPF, OF BERLIN, GERMANY.

MACHINE FOR MANUFACTURING TRIPPLICATE NOTEBOOKS.

Application filed June 11, 1927, Serial No. 198,198, and in Germany June 17, 1926.

My invention relates to improvements in machines for manufacturing triplicate note books, and more particularly in machines of the type in which the note books are made from webs of paper or other suitable material folded into meander-form and having suitable matter printed thereon. The object of the improvements is to provide a machine of this class in which the triplicate note book is made from a web folded into meander-form, and additional sheets placed between successive pairs of folded sheets of the web and cooperating therewith for making three records. With this object in view my invention consists in providing a machine in which a web of paper or the like is taken from a roll thereof, passed through suitable printing apparatus, gluing apparatus and folding apparatus, and in which further sheets of paper or the like similar or different in character and material from the character and material of the said web are supplied by feed mechanism to the said web and applied to the glued portion thereof prior to folding the web, so that the said sheets are folded together with the web. In the preferred construction the sheets are cut on the machine from a second web placed on a roll.

When using the note book made by my improved machine I need a single carbon paper for making records on the note book, the said carbon paper being prepared at both sides, and further, the said carbon paper need be fixed at one end of the book only, that is either at the top or at the bottom thereof. Another important feature of my improved note book resides in that the top of all the sheets is always located at the same side of the book, in which respect my note book is distinguished from triplicate note books heretofore made from a single web.

For the purpose of explaining the invention an example embodying the same has been shown in the accompanying drawings in which the same reference characters have been used in all the views to indicate corresponding parts. In said drawings,

Fig. 1, is a diagrammatical elevation showing the machine as a whole, the said machine comprising mechanisms heretofore used for similar purposes and novel mechanisms provided for performing novel functions,

Fig. 2, is a similar elevation on an enlarged

scale showing old parts of the machine combined with the novel mechanisms thereof, 55

Fig. 3, is a detail sectional view on an enlarged scale showing the main part of the glue applying mechanism,

Fig. 4, is a detail sectional view showing 60 the means for perforating the web,

Fig. 5, is an elevation looking from the left of Fig. 4,

Fig. 12, is a perspective view showing the web and sheets being folded into a triplicate note book, and

Fig. 13, is a detail view showing the mechanism for folding the web having the sheet 85 attached thereto.

Some of the mechanisms, and more particularly the mechanism for feeding and printing a web of paper or the like, and folding the same into meander-form are known 90 in the art, and I have illustrated the said parts in Fig. 1 in a diagrammatic way as far as is necessary in order to illustrate the co-operation of the said old parts with the novel mechanisms.

In the example shown in Fig. 1 my improved machine comprises a frame composed of a base member 100 having uprights 101, 102 and 103. On the uprights 101 the mechanisms for feeding and printing the web of 100 paper have been illustrated, the said web having received the reference character I, III indicating the sheets to be folded therefrom. The said web I, III is taken from a roll 1 and passed over rollers 2, 3, 4, 5 for 105 printing thereon suitable matter and numbers, the said printing being made, if desired,

in different colors, as is known in the art. From the said printing rollers the web is passed over a guide roller 13 and through a glue applying apparatus comprising a trough 6^a containing glue, a glue transmitting roller 6^b, a glue applying member 6^c adapted to take a certain amount of glue from the roller 6^b and to carry the same to the web of paper, the said paper being passed over a roller 6^d. From the gluing apparatus the web I, III is passed over a roller 7, and while moving over the same a sheet II of paper or other suitable material is applied thereto with one of its edges in position for being placed on the stripe of glue applied to the web. From the roller 7 the web I, III having the sheets II glued thereto is carried further to the folding apparatus indicated in Fig. 1 by the numeral 12, the said folding apparatus being adapted to fold the web and sheets into triplicate note books.

The sheets II are cut from a web 8 trained on a roller mounted at 104 and passed over printing rollers such as 9, a perforating apparatus 10, a cutting apparatus 11 and an endless band 105 trained on rollers 17 and 18 and adapted to supply the cut sheets II to the roller 7 and the web I, III. In view of the fact that one sheet II is combined with two successive sheets I and III, the circumferential velocity of the rollers supplying the web 8 is one half that of the rollers supplying the web I, III, and after a sheet II has been cut from the web by means of the mechanism 11, the tape 105 carries the same at increased velocity to the roller 7, where it is temporarily arrested by a rockable arresting member 6 adapted to be rocked out of the path of the sheet at the proper time for permitting the end of the sheet to be applied to the glued portion of the web.

In the following I shall describe the novel elements of the machine and their cooperation for forming the webs into a triplicate note book.

Referring at first to the glue applying apparatus illustrated in detail in Figs. 2 and 3, the said glue applying apparatus comprises the trough 6^a above referred to, the rotary roller 6^b adapted to take the glue from the trough 6^a, a wiper 6^e, the glue applying member 6^c and the roller 6^d on which the web I, III is trained. The glue carried upwardly by the roller 6^b is taken up by the member 6^c and transmitted thereby at the proper intervals to the web I, III. The construction of the member 6^c is shown in detail in Fig. 3. On a rotary shaft 34 two blocks 30, 31 are mounted, the said blocks being clamped together by screws 32 and 33. At one of their ends the said blocks are formed with a recess 106 in which the glue applying member 6^c is mounted so as to have a slight play in radial direction. The said glue applying member 6^c is in the form of a bar

disposed longitudinally of the roller 6^d and having a length equal to the breadth of the web I, III. The member 6^c is formed with flanges 107 and 108 by means of which it is confined within the recess 106, the said flanges permitting slight radial movement of the member 6^c. Springs 35 disposed in bores 109 tend to push the member 6^c outwardly and into yielding engagement with the roller 6^b and the web trained on the roller 6^d. The rollers 6^b and 6^d and the member 6^c have equal circumferential velocities, and by the rotation of the said parts the member 6^c takes up a small amount of glue and applies the same to the web. It will be understood that the breadth of the member 6^c is only a few millimeters, so that a very small amount of glue is applied to the web.

By the said apparatus a narrow stripe of glue is applied to the web, which stripe is shown in Fig. 2 at 109^a. As appears from the said figure, the said stripe is located at the side adapted to engage the roller 7, so that the sheet II placed with its edge against the said stripe is firmly pressed thereon.

The mechanism for taking the web 8 from the roll thereof and the printing apparatus may have any known or preferred construction, and I deem it not necessary to describe the same in detail. For perforating the web the mechanism shown in Figs. 4 to 6 is provided. As shown in the said figures and in Fig. 2, the said mechanism comprises two rollers 37, 39, the roller 37 being adapted to have the web 8 trained thereon, and being provided with one or more grooves 36 disposed longitudinally thereof and adapted to receive the edge of the perforating blade 38. As is shown in Fig. 6, the said blade is formed with a series of points 111. One or more blades 38 are mounted on the roller 39, and as shown, the blade is fixed to a bar 40 by means of screws 112, and the said bars are secured by means of screws 41 to a block 42 having tapering side walls and engaging in circumferential dovetailed grooves 43 made in the roller 39, the said blocks being fixed in position by screwing down the screws 41 and pressing the blocks 42 into engagement with the dovetailed faces of the grooves 43. The roller 37 and the edges of the blades 38 have equal circumferential velocity, and when rotating the said parts relatively to each other in the same direction the web 8 is perforated by the blades 38 without being separated thereby into sheets.

After the web 8 has thus been perforated at suitable parts it is supplied to the cutting apparatus comprising a pair of rollers 11^a and 11^b. The roller 11^a is formed with one or more longitudinal grooves 11^d adapted to receive the edge of the blade or blades 11^c. The said blade 11^c is fixed to a bar 11^e by means of a screw 11^f and a clamping rail 11^f. While cutting the web 8 must be held in

position on the roller 11^a at a part close to the blade 11^c; and for this purpose a slide 11^e is mounted in a substantially radial groove 11^m and acted upon by a spring 11^k tending to force the same outwardly. The said block 11^e is formed with radial recesses 11^h and 11ⁱ, the recess 11^h enclosing the rail 11ⁱ, and the slot 11^j enclosing the head of the screw 11^l. The spring 11^k tends to force the block 11^e outwardly and into claiming engagement with the web 8 being cut by means of the blade 11^c.

After the web 8 has been cut into sheets, the said sheets are transmitted between guide members 16 to a pair of endless tapes 105 and 114, the tape 114 being trained on rollers 115, 116 and on the roller 7. The velocity of the said tapes is larger than the circumferential velocity of the roller 11^a and 11^b, so that the sheets are rapidly carried away and to the rollers 7 and 18. When arriving between the said rollers the front edge of the sheet is temporarily arrested by the member b in position for being gripped by gripping needles 63 provided on the roller 7. The arresting mechanism has been shown in detail in Figs. 10 and 11. The arresting member b consists of a plurality of fingers b carried each by a rocker 19 mounted on a shaft 52. At the ends remote from the fingers b the rockers carry eyes 53 secured to a common rod 54 supported at its ends on arms 55, rockingly mounted on the shaft 52. On the arms 55 rollers 58 are mounted which are in engagement with a cam 60 formed on a circular rail 61 fixed to the end face of the cylinder 7. To the arms 55 springs 56 are attached, which are connected to relatively fixed parts 57 of the frame of the machine, and which tend to rock the arms 55 into the arresting position shown in Fig. 2 in full lines. When the needles 63 are pushed outwardly in the manner to be described hereinafter, the cam 60 rocks the arms 55 into the position shown in Fig. 2 in dotted lines thus putting the spring 56 under tension. Now the fingers b are in inoperative positions permitting the sheets to be carried along by the needles 63. After the sheet has passed the fingers b, the cam 60 releases the arm 55 thus permitting the spring 56 to rock the arms 55 into operative positions.

The construction of the needles 63 and the operating mechanism thereof has been shown in Figs. 8 and 9. The cylinder 18 is provided with several sockets 62 permitting the passage of the needles 63 into the same. The needles 63^a of each needle mechanism 20 are screwed into a bolt 63 fixed to a bar 65 at 64. The bar is provided at its ends with rollers 66 engaging in a cam groove 21. As appears from Fig. 8, the said cam groove is provided, at parts corresponding to the needle mechanisms mounted on the roller 7, with rises 116 by means of which the needles 63

are pushed outwardly through the sheets of paper and into the sockets 62, the said rises being located so that the needles are advanced whenever a pair of rollers 66 is in the position shown in Fig. 8.

The operation of this part of the machine is as follows:

A sheet II arriving with its front end between the rollers 7 and 18 is arrested by the fingers b while the rollers 7 and 18 continue their rotary movement. When a set of needles 63 arrives in the position shown in Fig. 8, the said needles are pushed outwardly and through the sheet of paper, and simultaneously the fingers b are rocked into the position shown in Fig. 2 in dotted lines thus permitting forward movement of the sheet taken up by the needles 63. After the sheet has been carried by the needles 63 into position for engagement with the glued portion 85 of the web I, III the needles 63 are retracted, the rollers 66 being moved inwardly within the cam groove 21. Now the sheet II is held in position between the outer face of the roller 7 and the web I, III, and it is pressed against the glued portion thereof, so that it sticks to the web after leaving the roller 7 in the manner indicated in Fig. 2.

In Fig. 12 I have shown the web I, III with the sheets II attached thereto in the state of being folded. The sheet II is glued to the web at 71 and its free end has been indicated by the numeral 70.

Fig. 13 shows the mechanism for folding the web and sheet into meander-form. In the said figure the numerals 12 indicate the folding rollers. Each folding roller 12 is provided with a recess 80 extending the whole length thereof, and on shafts 81, 81 folding fingers 84 are mounted, which are adapted to be operated from a cam member (not shown) through the intermediary of links 83, 83^a, a bell crank lever 117 and an arm 118. The recesses 80 are displaced relatively to each other, and also the fingers 84 are mounted on the respective shafts 81, 81 so as to be moved in opposite directions, so that the folding fingers of one set are removed from the roller while the folding fingers of the other set are moved towards the same.

The sheet II which is glued to the web I, III is preferably made of transparent material. It will be thus be seen that if a carbon is inserted immediately under this sheet II, the carbon being coated on both sides, a reverse impression will be obtained on the sheet II and a direct impression on that part of the folded sheet I, III which lies directly beneath the carbon. Another single coated carbon sheet is then placed in the next fold of the sheet I, III which will produce a direct impression on the lower fold. In this way three carbons are obtained, one on the transparent sheet and one on each of the two opaque folds. The writing on the transpar-

ent sheet will, of course, be reversed and must be observed through the sheet. It will be therefore seen that by writing on the upper leaf of applicant's note book three carbons will be produced, and only two carbon sheets need be inserted, the insertion being made from the same side of the book in each case. The book therefore presents distinct advantages over note books which have been 10 heretofore developed.

While in describing the invention reference has been made to a particular example embodying the same I wish it to be understood that my invention is not limited to the construction shown in the drawings, and that various changes may be made in the general arrangement of the apparatus and the construction of its parts without departing from the invention.

20 I claim:

1. A machine for manufacturing triplicate note books, comprising means for feeding a web, means to feed sheets to said web and to attach one end of each sheet to the 25 web, and folding means adapted to fold the unsevered web with the sheets carried thereby into continuous triplicate books.

2. A machine for manufacturing triplicate note books, comprising means for feeding a 30 continuous web, means for attaching separate sheets to said web at spaced points thereon, and means for folding said web so as to form triplicate books of the web and attached sheets.

35 3. A machine for manufacturing triplicate note books, comprising means for feeding a web, means to apply an adhesive to said web, means to feed sheets to said web into position for placing the same against said glued 40 portions, and folding means adapted to fold said web with the sheets carried thereby into triplicate books.

4. A machine for manufacturing triplicate note books, comprising means for feeding a 45 web, means to apply an adhesive to said web, means to feed a second web, means for cutting said web into sheets, means to feed said sheets to said first-named web into position

for being pressed against the glued portions thereof, and means for folding said first-named web with the sheets attached thereto into a triplicate book. 50

5. A machine for manufacturing triplicate note books, comprising means for feeding a web, means to apply an adhesive to said web, 55 means to feed a second web, means for cutting said web into sheets, means to feed said sheets to said first-named web into position for being pressed against the glued portions thereof, and means for folding said first-named web with the sheets attached thereto into a triplicate book, the velocity of the feeding means of the first-named web being the double of that of the feeding means of the second web, and the means for feeding 60 the cut sheets having a velocity substantially equal to that of the feeding means of the first-named web. 65

6. A machine for manufacturing triplicate note books, comprising means for feeding a 70 web, means to apply an adhesive to said web, means to feed sheets to said web into position for placing the same against said glued portions, and folding means adapted to fold said web with the sheets carried thereby into 75 triplicate books, said means to apply adhesive comprising a supply of the adhesive, a roller adapted to be coated with said adhesive, and a revolving elongated member adapted when being revolved to make contact with 80 said roller and with the web being fed.

7. A machine for manufacturing triplicate note books, comprising means for feeding a web, means for attaching sheets to said web, and folding means adapted to fold said web 85 with the sheets carried thereby into triplicate books, said web feeding means comprising a roller adapted to have the web passed thereon, and gripping needles radially movable in said roller and in position for gripping the sheets being fed and for carrying the same to the web being passed on said roller. 90

In testimony whereof I hereunto affix my signature.

RUDOLF GOMPF.
